CALENDAR RING FOR A WRISTWATCH

Sadao Fujinami, Hatogaya, Japan, assignor to Orient
Tokei Kabushiki Kaisha (also trading as Orient Watch
Co., Ltd.), Tokyo, Japan

Filed Feb. 29, 1972, Ser. No. 230,550

Term of patent 14 years

Int. Cl. D10—07

U.S. Cl. D10—122

FIG. 1.

FIG. 2.

FIG. 1 is a top plan view of a calendar ring for a wristwatch showing my new design; and

FIG. 2 is a top plan view of another embodiment of my new design.

The calendar rings are conventionally flat without patterns on edges or rear sides.

I claim:

The ornamental design for a calendar ring for a wristwatch, as shown.
